Primary Examiner — Austin Murphy*(74) Attorney, Agent, or Firm* — Oliff PLC(57) **CLAIM**

The ornamental design for an image display device, as shown and described.

DESCRIPTION

FIG. 1 is a rear, top, right-side perspective view of an image display device;

FIG. 2 is a front, bottom, left-side perspective view thereof;

FIG. 3 is a front view thereof;

FIG. 4 is a top view thereof;

FIG. 5 is a right-side view thereof;

FIG. 6 is a left-side view thereof;

FIG. 7 is a rear view thereof; and,

FIG. 8 is a bottom view thereof.

The broken lines depict environmental subject matter only and form no part of the claimed design. The dot-dash lines depict a boundary between claimed and unclaimed subject matter, and form no party of the claimed design.
